[57] **CLAIM**

The ornamental design for a bottom portion of a shoe outsole, as shown and described.

DESCRIPTION

FIG. 1 is a bottom plan view of a bottom portion of a shoe outsole showing my new design;

FIG. 2 is a profile view taken along line 2—2 of FIG. 1; FIG. 3 is a profile view taken along line 3—3 of FIG. 1; and, FIG. 4 is a perspective view of the bottom portion of a shoe outsole of FIG. 1.

The broken line showing of a shoe upper and shoe sole periphery is for illustrative purposes and forms no part of the claimed design.
